Primary Examiner — Deanna L Pratt*Assistant Examiner* — Harold Blackwell, II(74) *Attorney, Agent, or Firm* — Sughrue Mion, PLLC(57) **CLAIM**

The ornamental design for a shield for vacuum circuit breaker, as shown and described.

DESCRIPTION

FIG. 1 is a front, top and right side perspective view of a shield for vacuum circuit breaker, showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a cross-sectional view thereof; taken along line 7-7 of FIG. 5.

1 Claim, 5 Drawing Sheets(56)
